(57) **CLAIM**

The ornamental design for a polycrystalline diamond compact with a raised surface and a groove therein, as shown and described.

DESCRIPTION

FIG. 1 is a top perspective view of a polycrystalline diamond compact with a raised surface and a groove therein showing our new design;

FIG. 2 is a bottom perspective view of a polycrystalline diamond compact with a raised surface and a groove therein of FIG. 1;

FIG. 3 is a top plan view of the polycrystalline diamond compact with a raised surface and a groove therein of FIG. 1;

FIG. 4 is a bottom plan view of the polycrystalline diamond compact with a raised surface and a groove therein of FIG. 1;

FIG. 5 is a side elevation view of the polycrystalline diamond compact with a raised surface and a groove therein of FIG. 1; and,

FIG. 6 is another side elevation view of the polycrystalline diamond compact with a raised surface and a groove therein of FIG. 1.

The broken lines show portions of a polycrystalline diamond compact with a raised surface and a groove therein which forms no part of the claimed design.
